(No Model.)

W. H. CRITTENDEN.
ROAD SCRAPER.

No. 448,412.

Patented Mar. 17, 1891.

Attest,

Frank. Willson.
H. H. Willson.

Inventor:

William H. Crittenden
By Henry F. Willson
his attorney in fact.

UNITED STATES PATENT OFFICE.

WILLIAM H. CRITTENDEN, OF BELDEN, OHIO.

ROAD-SCRAPER.

SPECIFICATION forming part of Letters Patent No. 448,412, dated March 17, 1891.

Application filed October 30, 1890. Serial No. 369,802. (No model.)

To all whom it may concern:

Be it known that I, WILLIAM H. CRITTENDEN, a citizen of the United States, residing at Belden, in the county of Lorain and State 5 of Ohio, have invented a new and useful Road-Scraping Machine, of which the following is a specification.

My invention relates to that class of road-scrapers which will clean out the ditch beside 10 the road and throw the dirt in toward the center thereof, and at the same time level it. I attain these objects by the mechanism illustrated in the accompanying drawings, in which—

15 Figure 1 is a plan view. Fig. 2 is a side elevation. Figs. 3, 4, 5, 6, 7, 8, 9, and 10 are detached views of the several details. Fig. 11 is a detailed sectional view showing the method of constructing the scraper and securing the parts together.

Similar letters refer to similar parts throughout the several views.

In the drawings, A represents the scraper, which consists of a plank about two feet in 25 width and about eight feet in length, which is placed diagonally across the line of draft, as seen in Fig. 1, the upper edge inclining somewhat to the rear, as seen in Fig. 2, and is held firmly in position by studs B. To the 30 lower front edge of this plank is secured a cast-iron strip a, formed as seen in Figs. 3 and 9. To and over this strip and over the entire front surface of plank A is secured a strip of sheet-steel a', which is curved to fit, 35 and its lower edge forms the cutting-edge of the scraper.

C represents an adjustable landside, having a point c curved inward (see Figs. 1 and 10) to assist in overcoming the side draft. 40 Said landside extends back about eighteen inches, and is secured in position so as to render it adjustable vertically, giving more or less dip to the point, as desired, thus adapting it to the conditions of the soil where used. 45 Said landside is secured in position by means of pin d', which fits through slot w, and is provided with a countersunk head, which holds the plate firmly in position, but admits of it working freely in a vertical direction 50 over the slot. At the rear end of the landside a lever d is strongly pivoted at its lower

end to the frame-work of the scraper, and also to the landside just above, as seen in Fig. 9. When the lever d is forced forward, the point is forced forward and downward as 55 much as is desired. The reverse movement returns the landside to a level with the under surface of the scraper. At the opposite end of the scraper a supplementary scraper J is attached, which extends at nearly a right 60 angle thereto, for the purpose of holding the accumulated dirt and carrying it forward to a point where it may be advantageously deposited. This attachment may be removed when desired. Said supplemental scraper J 65 is firmly secured to the main scraper by means of a wrist-pin r, which extends through the rear end of the supplemental scraper and receives a key S. Said scraper J is held in place by stops t, which keep it from turning 70 on pin r. The outer end is prevented from swagging back by means of a rod u, which connects it with the pole C'.

The curved steel plate which forms the shear or cutting-edge of the scraper is 75 strengthened and supported by means of the cast-iron strip a, to which it is secured, thus making it practicable to use very much thinner steel plate than has been used, saving considerable in weight of material and expense of construction.

C' represents a pole or tongue, which is at the rear secured to center stud B and extends forward and is secured to and is supported by the axle of a suitable truck, by 85 which it is drawn. Braces D D extend diagonally forward from the outside studs B B, and at their forward end are secured to pole C'. Brace E and iron braces f f extend also from the pole to the scraper for the purpose 90 of giving strength and rigidity to the apparatus.

To the rear of the center of the scraper is hinged a platform F, on which the operator may stand. (See Figs. 1, 2, 5, and 6.) At the 95 rear of platform F and directly under it is a lining-wheel G, which is secured in suitable bearings to lever H. Said lever is pivoted to the under side of the platform, as seen at g, Figs. 2 and 6. Lever H extends forward to 100 near the front edge of the platform, where its end locks into a segment h, which is provided

with a journal that extends upward through the platform, where it may be oscillated by means of lever *i*, which is pivoted to the upper side of the platform and engages said segment, as seen in Figs. 2 and 5. By means of this device the lining-wheel may be deflected from the line of draft to the right or left, as desired, and thus very materially assisting in controlling the direction of the apparatus, and by a skillful operator may be easily made to wholly overcome the powerful tendency to side draft. This result is greatly facilitated by the curved point of the landside, without which it would be impossible to accomplish the object, as any divergence from the line of draft to the right would induce a corresponding divergence to the left of the forward end.

Wheels *II* are secured in position by means of a system of compound levers, by which the scraper, platform, and lining-wheel are elevated at one or both ends from the ground for the purpose of turning around or transportation. The journals of wheels *II* are secured in suitable bearings formed in bent levers *j*. (See Figs. 2, 7, and 8.) The lower short ends of these levers are pivoted, as seen at *k*, to arms which are rigidly secured to back or rear side of the scraper. The upper

ends of said levers are connected to clutch-levers *m* by means of rods *l*. Said clutch-levers are also pivoted at their lower ends to the edges of the platform *F*, and are provided with the ordinary clutch, which takes hold of and is held rigidly in position by semicircular racks. By a judicious management of these levers the scraper may be easily raised or lowered at either end to meet the requirements of the grade and distribute the dirt as desired.

What I claim as new, and desire to secure by Letters Patent, is—

1. In road-scrappers, the combination of the cast strip *a*, the board *A*, and the steel strip *a'*, covering the front surface of said board and cast strip, the same being securely bolted together, in the manner and for the purpose specified.

2. The adjustable lining-wheel *G*, in combination with the curved point *c*, for the purpose of steering the apparatus and controlling the side draft, each part being constructed in the manner specified.

WILLIAM H. CRITTENDEN.
